ATTACHMENT PLUG

James E. Flood, Norwich, Conn., assignor to The Plastic Wire & Cable Corporation, Norwich, Conn., a corporation of Connecticut

Application January 12, 1946, Serial No. 640,921

2 Claims. (Cl. 173—361)

1

This invention relates to electrical plugs such as are attached to appliance and extension cords to be detachably connected to plug-receptacles.

An object of this invention is to provide an attachment plug which is economical to make and assemble with the wire connected contact blades and yet in which, when assembled, the anchored ends of the blades are permanently secured in the plug body against removal in any manner except by the destruction of the body of the plug.

Heretofore, in plugs of this type in which spaced blade-receiving passages pass through the plug and converge and merge with the cord-receiving cavity at the opposite end of the plug it has been the practice to connect the blades to the conductors, spread the end of the plug having the cord-receiving cavity until the cord-receiving cavity is in substantial alignment with the blade-receiving passages and then draw the assembled blades and conductors in from the back of the plug through the passages into position with the blades projecting from the front of the plug. This has been an expensive operation and requires a good quality of rubber in the plug body to permit the extension thereof. Many times in the assembling operation the end of the insulation on the conductor engages the edge of the plug body and is stripped back unless precautions are taken to protect this end.

The present invention overcomes these difficulties by making the body of flexible material and providing the usual integral solid central portion between the blade-receiving passages of the body with a bore of a diameter to receive the conductor, which bore is preferably in a line with the conductor-receiving aperture at the base of the plug body. The bore is connected with the blade-receiving passages by slits passing through the central core.

When the plug is assembled according to the present invention the conductor is passed through the cord-receiving aperture and the bore in the central core. The contact blades are attached to the wires of the conductor and the connected blades are then withdrawn into the plug with the blades held and guided by the blade-receiving passages and the wires passing through the slits in the central core until the wires have reached the conductor-receiving cavity and the blades are in anchored position. Thereafter, the bore in the central portion is plugged up with an elongate filler which extends for substantially the full length of the central core and the slits connecting the bore to the passageways are permanently

2

sealed, thus providing a substantially rigid integral central core for holding the blades in the passageways against removal therefrom without destruction of the body of the plug.

5 A feature of the present invention resides in the arrangement wherein the conductor and blades may be assembled with the plug without in any way distorting the body of the plug, thus permitting less resilient material to be used.

10 Another feature of the invention resides in the making of the filler of a different material or of a material of contrasting color to serve as identifying means for the plug or circuit in which the plug is employed.

15 Other features and advantages of the invention will be apparent from the specification and claims when considered in connection with the drawings in which:

Figure 1 shows a sectional view taken along line 1—1 of Fig. 2.

Fig. 2 shows an end view of the plug body.

Fig. 3 shows a sectional view taken along line 3—3 of Fig. 4.

20 Fig. 4 is an end view of the plug body with the blades in place and the central bore and slits closed.

Fig. 5 shows a view of the blades and plug body and filler or closure in position to be assembled in the plug body.

25 30 As shown in the drawings, the plug body 10 of flexible material, such as rubber, synthetic rubber, polyvinyl chloride and the like synthetic resins or acetates, has a conductor-receiving aperture 11 formed at the back end thereof. This opens into a conductor-receiving cavity 12 which has a pair of blade-receiving slots or passages 13 extending therefrom to the forward end of the plug on opposite sides of an integral central core 14. The outer walls 14a of the central core

35 40 form one wall of each of the passages 13. The walls 14a are provided with means for cooperating with the blade to anchor the blades in the passage. While this means may vary in form it is herein illustrated as a notch 15 formed in the wall and providing an abutment 15a.

45 50 As is shown in Figs. 1 and 2, the central core of the plug has a bore 16 extending therethrough. The bore is preferably in line with and of the same shape as the conductor-receiving aperture at the other end of the plug although it may vary in size and shape as required. The aperture and bore form a passage through which the conductor may be readily passed without substantial distortion of the plug and into a position in which

the blades may be attached thereto as will be described.

The central core on each side of the bore is provided with a slit 17 which extends from the bore and intersects the wall 14a of the passage.

The conductor may have any type of insulation 19 thereon and is provided with two insulated wires 20 connected to the contact blades 21 which project from the front face of the plug for insertion into the usual plug-receptacle.

The blades are anchored in the blade-receiving passages by tangs 22 lanced therefrom and projecting rearwardly so as to engage the abutment 15a when the blades are anchored in position. The inner ends of the blades are bent inwardly as shown at 21a and bear against the walls of the passage to assist the tangs in holding the blade against movement in either direction.

After the blades and conductor have been assembled with the plug a filler member 23 having the shape and substantially the length of the bore in the central core is inserted and permanently secured therein. This filler closes the opening at the front of the plug and prevents accidental passage of foreign matter into the body and since it extends for substantially the full length of the central core reinforces the blade-receiving passages and holds the portion of the wall 14a having the blade anchoring means against inward displacement which might release the tang. The slits are also permanently secured together, thus forming a substantially rigid central core which holds the blades in anchored relation against separation without destruction of the plug body.

The filler member may be in the form of a rod or plug or it may be a plastic mass which will undergo a phase change and harden in the bore. It may be made of the same material as the body or of any compatible material and may be permanently secured therein and the slits permanently sealed by suitable cements or adhesives. If the filler member is made of the same material as the body it can be dipped into a solvent therefor and the walls of the bore coated with the solvent, so that when it is inserted into the bore, the surfaces produced thereon by the solvent will cause the filler and central bore to become a single unit. The solvent may also be applied to the walls of the slits to soften them so that when pressed together they will merge and form the central core into a single unit.

Various pigments or colors may be incorporated in the material of the filler member and the exposed contrasting colors of the body and the member may serve as identification means for the plug or for the circuit in which the plug is used.

The plug of the present invention has the advantage of being provided with completely pre-formed blade-receiving passages and anchoring means for supporting the blades while the filler member is being inserted and the slits sealed to form the unitary central core for permanently securing the blades to the plug.

If desired, the end of the insulation 19 may be coated with an adhesive or bonding medium so that it may be secured to the plug and held against stripping.

In assembling the plug of the present invention the conductor is fed through the conductor-receiving aperture 11 and through the bore 16 to the position shown in Fig. 5. The aperture and bore are preferably of sufficient size as to permit the conductor 18 to pass without danger of the

insulation 19 being stripped back. The ends of the wires are secured to the blades by soldering or any other suitable means and the blades and conductor are withdrawn into the plug with the conductor disposed in the bore and the blades being located in the blade-receiving passages and the wires passing through the slits in the central core. The assembled conductor and blades are drawn to the position in Fig. 3, wherein the wires 10 are located in the conductor-receiving cavity 12 and the blades are in anchored position with the tangs 22 in engagement with the shoulder 15a.

The surfaces of the bore and filler member are then rendered adhesive and the member is 15 inserted into the bore. The walls of the slits in the central core are rendered adhesive and the whole central core permanently united together by pressure exerted on the walls. It will be seen that the filler extending for substantially the 20 length of the core backs up the thin section of the central core between the passageway and the bore and holds the anchoring means in position.

With the plug of the present invention the assembling operation can be carried out without 25 requiring that the body of the plug be extended. Hence, a less resilient and flexible material may be used in place of a highly resilient material necessary when the plug was stretched or deformed as heretofore. Furthermore, the slits of 30 the present invention not only permit the wires to move into the cavity as the blades are pulled into position in the blade-receiving passages but also permit the anchoring tangs to readily move into the notches without tearing or damaging 35 the walls of the slot.

The blades will be held in their preformed passages by the preformed anchoring means therein and may not be removed without destroying the body of the plug.

40 Variations and modifications may be made within the scope of this invention and portions of the improvements may be used without others.

I claim:

1. An attachment plug having a body of flexible material provided with blade-receiving and anchoring passages therein on each side of a central core and a conductor-receiving aperture merging with the inner ends of said passages; and a conductor disposed in the aperture and having blades provided with anchoring tangs connected thereto and anchored in the passages in the body, said core having a slit ending in said passages and having a recess facing each respective passage; a filler recess located intermediate the ends of said slit; and a separate filler member corresponding in shape to said filler recess for insertion in said filler recess after assembly of plug, blades and attached conductors, said slit having walls which may be resiliently urged apart to facilitate the passage of the conductor and its wires and attached contact blades and anchoring tangs into the body from the front thereof during assembly when the body is flexed to cause the slit to open, and said recess 60 cooperating with and being engaged by said anchoring tangs on the blades to anchor the blades in the passages.

2. The invention as defined in claim 1, wherein in adhering means is applied to the filler member and recess therefor to seal the filler member in the recess permanently.

JAMES E. FLOOD.

Certificate of Correction

Patent No. 2,537,820

January 9, 1951

JAMES E. FLOOD

It is hereby certified that error appears in the printed specification of the above numbered patent requiring correction as follows:

Column 3, line 6, after the word "conductor" insert *18*; column 4, line 9, after "position" insert *shown*; column 6, line 11, list of references cited, for "Apr. 28, 1924" read *July 1, 1926*;

and that the said Letters Patent should be read as corrected above, so that the same may conform to the record of the case in the Patent Office.

Signed and sealed this 13th day of March, A. D. 1951.
